UNITED STATES PATENT OFFICE

JAMES N. BAKER, OF TOWSON, MARYLAND, ASSIGNOR TO THE BLACK AND DECKER MANUFACTURING COMPANY, OF TOWSON, MARYLAND, A CORPORATION OF MARYLAND

BIT HOLDER

Application filed October 7, 1930. Serial No. 486,914.

In the operation of the various portable power hammers, pneumatic, electric and the like, a considerable element of danger is involved through the tendency to project the bit or steel from the tool when for any reason the motor is permitted to run with the bit out of contact with the work. While various means have been devised for retaining the bit in its socket, these, on account of their 5 rigid character, are apt to be broken or are found so inconvenient to operate when the bit is changed, that they are discarded by the workman so that from a practical point of view they are wholly ineffective for the 10 purpose in hand.

The present invention provides a bit holder of a resilient nature so that it avoids the danger of breaking due to the impact of the bit when it is projected forwardly by the 15 action of the hammer when not in contact with the work. The bit holder or retaining device is also capable of instantaneous operation in releasing the bit to be removed and engaging the one newly inserted, the resilient 20 feature contributing to the instantaneous operation of the retaining device and also serving to hold it in close engagement with the shank of the bit when in operation. The new bit holder is regarded as of increased efficiency and its construction is at 25 the same time greatly simplified and cheapened as compared to those now in use.

In the accompanying drawing I have illustrated the tool retaining device or bit holder 30 of the invention in the preferred form, the same being shown in its operative relation to the bit or steel as it is being called in practice and to the percussive tool or hammer, so much of the bit and percussive tool as is 35 necessary to a full comprehension of the invention being shown in connection with the bit holder.

In the drawing:

Figure 1 is a bottom plan view of the nose 40 of a portable power driven hammer or percussive tool equipped with a steel or bit, the latter being held in position by the retaining device of the invention.

Figure 2 is a vertical section on the line 50 2-2 of Figure 3 showing the nose of the

percussive tool fragmentarily, the steel or bit and the retaining device also being shown in elevation, a portion at one end of the retaining device being broken away and shown in section and the other end in full.

55

Figure 3 is an elevation showing the same subject matter looking in a direction at right angles to the direction of observation in Figure 2.

Referring to the drawing by numerals, each of which is used to indicate the same or similar parts in the different figures, the construction shown comprises the nose 1 of a percussive tool or hammer, having a socket 2 in which is seated the bit or steel 3, the same being held in position by the retaining device 4, which is the subject of the invention.

In accordance with the prevailing practice, the bit or steel 3 is provided with a circumferential shoulder 5, which limits the extent to which the bit 3 can be inserted in the socket 2. For the purpose of positioning the bit the surface of the shoulder 5 at 6 disposed toward the socket end of the shank, contacts the outer end of the nose of the percussive tool at 7, the opposite surface of the shoulder 5 at 8 being disposed toward the operative end of the bit or steel which engages the work. The retaining device 4 comprises a yoke 9 which as seen in side elevation, Figure 2, is U shaped, and the cross arm of the U at 10 is as shown in plan, Figure 1, bent in the form of a horizontally disposed U or loop 11, which is preferably semicircular or substantially so and of a radius but slightly greater than that of the bit or steel shank which is ordinarily round so that it engages the same closely for about one half of its periphery. However, the exact contour of the bit is not absolutely essential, the retaining device being capable of engaging an octagonal, a hexagonal or even a square bit or steel.

Referring now to Figure 3 and also to the bottom plan, Figure 1, it will be noted that the legs 14 of the loop 11 extend in a horizontal direction from the loop 11 well beyond the center of the shank of the bit or steel, and the legs 15 of the yoke 9 are inclined upwardly and backwardly from the ends of legs 14

in to the central axial plane which may be identified as the plane of the section, Figure 2, where it intersects the nose 1. The upper ends of these legs are flat as shown at 16, 5 Figure 3, the plane of said end surfaces 16 being at right angles to the axis of the steel or bit 3, and the construction described being widely variable.

To cooperate with the retaining device of 10 the invention, the nose 1 of the percussive tool or hammer is provided with two oppositely projecting lugs 17, 18, the central radial planes of which including the axis of the bit or steel or coincident with the plane 15 of Figure 2 where it intersects nose 1. These lugs are bored at 20, 21, respectively, in a direction parallel to the axis of the bit and through these lugs as thus bored are passed two L shaped bolts 22, 24, the feet of the respective L's at the lower ends of said bolts at 25 being passed through suitable holes 26 in the upper ends of the legs 15 of the yoke 9. The L shaped bolts 22, 24 are provided at their ends opposite to the feed 24 with nuts 27 and suitable helical springs 28 encircle the shanks of these bolts, being compressed each between the adjacent lug 17, 18 on the hammer nose and the corresponding nut 27 so that the bolts 22, 24 are given an upward 30 tendency pressing the flat surfaces 16 on the upper ends of legs 15 against the bottom surfaces of ears or lugs 17, 18.

In the operation of the device, the loop 11 in the cross arm 10 of the yoke partially encircles and preferably engages the shank of the steel or bit below the shoulder 5. Thus when the bit is by any chance projected forward as by the operation of the hammer mechanism when the bit is not in contact with the work, the forward surface 8 of the shoulder 5 contacts the cross arm 10 of the yoke 9 at the loop 11 so that its release from the hammer nose is prevented. When it is desired to remove the steel or bit, the yoke is swung backwardly against the resistance of springs 28, the flat surfaces 16 and 29 substantially at right angles meeting in corner 23 acting in the nature of a cam or check held in contact with the surface of the corresponding lugs 17, 18 by the springs 28. In this operation the yoke rocks on the corners 23 to a position at right angles to the axis of the tool, the flat surface 29 being then held by springs 28 in contact with the lugs 17, 18, thus positioning the yoke till a new bit or steel has been inserted, or other such operation performed when the yoke is swung back into position again rocking on corner 23 till it is again held in close contact with the shank of the bit or steel by means of the springs 28 drawing the flat surfaces 16 on the ends of the legs of the yoke 9 against the lugs 17, 18 as will be fully described specifically and in detail a bit retainer embodying the features 665 of any invention in the preferred form in

order that the manner of constructing, applying and using the invention may be fully understood, however, the specific terms herein are used descriptively rather than in a limiting sense, the scope of the invention 70 being defined in the claim.

What I claim as new and desire to secure by Letters Patent is:

The combination in a portable power-driven hammer having a nose portion with laterally extending lugs and a bit with a transverse shoulder, the lugs having surfaces disposed toward the work of a retainer comprising a yoke, the yoke having in cross-arm with a loop adapted to encircle the shank of the bit beyond the shoulder, pins extending through the lugs and slidably therein parallel to the bit, the pins having pivots rigidly connected thereto and disposed at right angles to the pins, springs applying tension to the pins oppositely to the working stroke of the hammer, the yoke having cam members formed on its respective ends and apertured to receive the pivots on which the cam members and the yoke rotate, the cam members having substantially flat surfaces transverse to the length of the yoke adapted to engage the surfaces of the lugs whereby the yoke is held by the springs cooperating with the cams in engagement with the tool shank, said yoke being adapted to rock on said pivots, removing said cam surface from engagement with the lugs and the yoke from engagement with the tool shank, the cams having other substantially flat surfaces adapted to engage the lugs to hold the yoke in its disengaged position the tension of the springs being thereby increased as the yoke is rocked into and out of engagement with the shank and slightly relaxed when the yoke reaches either extreme 100 position when one or the other pair of cam surfaces bears on the lugs.

Signed by me at Towson, Baltimore County, Maryland, this 30th day of September, 1930.
